Primary Examiner — Darlington Ly(74) *Attorney, Agent, or Firm* — Baumgartner Patat Low; Marc Baumgartner(57) **CLAIM**

The ornamental design for a bicycle derailleur, as shown and described.

DESCRIPTION

FIG. 1 is a front and right side perspective view of a bicycle derailleur embodying my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines show portions of the bicycle derailleur that form no part of the claimed design.

1 Claim, 7 Drawing Sheets(56)
